US00D727300S

(12) **United States Design Patent**
Anderson et al.

(10) **Patent No.:** **US D727,300 S**
(b4) **Date of Patent:** **** Apr. 21, 2015**

(54) **EAR TIP TESTER**(71) Applicant: **Logitech Europe S.A.**, Lausanne (CH)(72) Inventors: **Jeff Anderson**, Camas, WA (US); **Neil O'Connell**, Seattle, WA (US); **Doug Ebert**, Portland, OR (US)(73) Assignee: **Logitech Europe S.A.**, Lausanne (CH)(***) Term: **14 Years**(21) Appl. No.: **29/476,844**(22) Filed: **Dec. 17, 2013**(51) LOC (10) Cl. **14-01**

(52) U.S. Cl.

USPC ..... **D14/223**(58) **Field of Classification Search**CPC H04R 1/10
USPC D14/223; D24/106, 173, 174; 181/129,
181/130, 135; 379/430, 431; 381/380, 381,
381/322, 328; 455/90.3, 575.1
